Attns,

UNITED STATES PATENT OFFICE.

JACOB CAYLOR, OF FAIRVIEW, ASSIGNOR OF ONE-HALF HIS RIGHT TO
CHARLES E. JONES, OF REDKEY, INDIANA.

IMPROVEMENT IN CULTIVATORS.

Specification forming part of Letters Patent No. 140,885, dated July 15, 1873; application filed
October 12, 1872.

To all whom it may concern:

Be it known that I, JACOB CAYLOR, of Fairview, in the county of Randolph and State of Indiana, have invented a new and valuable Improvement in Cultivators; and I do hereby declare that the following is a full, clear, and exact description of the construction and operation of the same, reference being had to the annexed drawings making a part of this specification, and to the letters and figures of reference marked thereon.

Figure 1 of the drawings is a representation of a side view of my invention. Fig. 2 is a top view of the same. Figs. 3 are detail views of the same.

This invention has relation to shovel-plows; and it consists in the construction and novel arrangement of the transversely-recessed block, having its outer face plated with metal, and the curved shovel-beams, having formed upon the front edge an eye used in connection with the adjustable diagonal braces, as hereinafter described and claimed.

Referring to the drawings, A designates the draft-beam; B B, the handles, bolted to the beam A at their forward ends, and supported at the rear by the perforated adjustable arms C, by means of which the handles may be adjusted to different heights. D D designate blocks, recessed transversely to fit close to the beam A, and arranged at the same pitch as the shovel-beams E E, which are made of iron and slightly curved outward and upward, and are fastened to the beam A by bolts passing through the blocks D D and the beam A. Upon the front end of each shovel-beam is formed an eye, e, for the purpose of connect-

ing said beams to the diagonal perforated braces F, which are fastened by means of wooden pins f, and secured in an adjustable manner to the draft-beam, so that they may be adjusted to regulate the depth of the plows.

To convert the plow from a double to a single plow the beams E E, braces F, and the foremost of the blocks D are removed. The left-hand beam, for instance, is then secured to the remaining or right-hand block, which will bring the shovel directly under the beam A. The forked brace G is then secured to the shovel and draft beams.

The brace G is perforated, and capable of adjustment to regulate the depth of the plow.

The blocks D are plated with metal at their outer face to prevent wear or splitting. This metal plate is shown at z on the drawings, and is constructed with a smooth outer surface to provide for the adjustment of the shovel-beam thereon at any proper or desirable angle.

What I claim as new, and desire to secure by Letters Patent, is—

In a cultivator, the combination of the transversely-recessed block D, having its outer face plated with smooth metal, the laterally-adjustable shovel-beam E, provided with the eye e and the adjustable perforated braces F, substantially as shown and described.

In testimony that I claim the above I have hereunto subscribed my name in the presence of two witnesses.

JACOB CAYLOR.
